SPECTACLE FRAME

Austin B. Belgard, Evanston, Ill.

Application July 13, 1953, Serial No. 25,923

Term of patent 14 years

(Cl. D57—1)

To all whom it may concern:

Be it known that I, Austin B. Belgard, a citizen of the United States, residing at Evanston, county of Cook, and State of Illinois, have invented a new, original, and ornamental Design for a Spectacle Frame, of which the following is a specification, reference being had to the accompanying drawing, forming a part thereof, in which:

Fig. 1 is a top plan view of a spectacle frame, showing my new design; Fig. 2 is a front view in elevation; Fig. 3 is a side view in elevation; and Fig. 4 is an enlarged sectional view, the section being taken as indicated at line 4—4 of Fig. 2.

I claim:

The ornamental design for a spectacle frame, as shown.
